US0D1031788S

(12) **United States Design Patent** (10) **Patent No.:** **US D1,031,788 S**
(45) **Date of Patent:** **** Jun. 18, 2024**

(54) **WEAR RESISTANT COATING**

(71) Applicant: **Ironhawk Industrial Distribution LLC**, Euclid, OH (US)

(72) Inventor: **Patrick Hawkins**, Rocky River, OH (US)

(73) Assignee: **Ironhawk Industrial Distribution LLC**, Euclid, OH (US)

(**) Term: **15 Years**

(21) Appl. No.: **29/696,936**

(22) Filed: **Jul. 2, 2019**

Related U.S. Application Data

(63) Continuation of application No. 15/418,019, filed on Jan. 27, 2017, now Pat. No. 10,400,404.

(51) **LOC (14) Cl.** **15-03**

(52) **U.S. Cl.** **D15/11**
USPC **D15/11**

CLAIM

I claim the ornamental design for a wear resistant coating, as shown and described.

DESCRIPTION

FIG. 1 is a top perspective view of a wear resistant coating; and,

FIG. 2 is a front view showing the wear resistant coating on a plow shoe.

The portions of the Figures shown in broken lines depict environmental structure, and form no part of the claimed design.

1 Claim, 2 Drawing Sheets
